DESIGN FOR A COMBINATION BATHROOM UNIT

John E. Kelley, Bangor, Maine

Application June 13, 1936, Serial No. 63,289

Term of patent 14 years

To all whom it may concern:

Be it known that I, John E. Kelley, a citizen of the United States, residing at Bangor, in the county of Penobscot and State of Maine, have invented a new, original, and ornamental Design for a Combination Bathroom Unit, of which the following is a specification, reference being had to the accompanying drawing, forming part thereof, in which

Fig. 1 is a perspective view of the combination bathroom unit in accordance with the present invention;

Fig. 2 is a view looking towards one end of the unit illustrated in Fig. 1; and

Fig. 3 is a view looking towards the other end of the unit illustrated in Fig. 1.

I claim:

The ornamental design for a combination bathroom unit, as shown.

JOHN E. KELLEY.
